UNITED STATES PATENT OFFICE.

HATTIE HULL TROUPE, DECEASED, LATE OF RELAY, MARYLAND; BY CALVIN F. TROUPE, EXECUTOR, OF RELAY, MARYLAND, ASSIGNOR TO SERVICE STAR LEGION, INCORPORATED, OF BALTIMORE, MARYLAND, A CORPORATION OF MARYLAND.

DESIGN FOR A BADGE OR SIMILAR ARTICLE.

Application filed April 25, 1924. Serial No. 9,405. Term of patent 7 years.

To all whom it may concern:

Be it known that HATTIE HULL TROUPE, formerly a citizen of the United States, and formerly residing at Relay, in the county of Baltimore and State of Maryland, deceased (CALVIN F. TROUPE, of Relay, Maryland, executor of HATTIE HULL TROUPE, deceased), did during her lifetime invent a new, original, and ornamental Design for a Badge or Similar Article; and I, the executor, do hereby declare the following to be a true specification of said design, reference being had to the accompanying drawing, forming part thereof.

The drawing is a front view of a badge or similar article showing the new design.

What is claimed is:

The ornamental design for a badge or similar article substantially as shown.

In testimony whereof, I have hereunto subscribed my name.

CALVIN F. TROUPE,
Executor of the estate of Hattie Hull Troupe, deceased.
